UNITED STATES PATENT OFFICE.

WILLIAM McCANCE, OF VERONA, NEW JERSEY.

DESIGN FOR A THUMB-WHEEL PROTECTOR.

42,874.

Specification for Design.

Patented Aug. 13, 1912.

Application filed April 25, 1912. Serial No. 693,237. Term of patent 7 years.

To all whom it may concern:

Be it known that I, WILLIAM McCANCE, a citizen of the United States, residing at Verona, in the county of Essex and State of New Jersey, have invented a certain new, original, and ornamental Design for a Thumb-Wheel Protector, of which the following is a specification, reference being had therein to the accompanying drawing.

In the drawings:—Figure 1 is a front elevation of the protector for the thumb wheel showing my design. Fig. 2 is a side elevation of my new design. Fig. 3 is a rear view thereof. Fig. 4 is a perspective view

of the thumb wheel showing my new design. Fig. 5 is a perspective view of the attachment shown applied to a portion of the typewriting machine.

I claim:—

The ornamental design for a thumb wheel protector, as shown.

In testimony whereof I hereunto affix my signature in presence of two witnesses.

WILLIAM McCANCE.
